(57) CLAIM

The ornamental design for a towel for workout and beach lounging, as shown and described herein.

DESCRIPTION

FIG. 1 is a front and left side perspective view for a towel for workout and beach lounging, showing my new design with the upper and side portions shown in a folded position thereof;

FIG. 2 is a front view of the towel for workout and beach lounging shown in FIG. 1 shown in an unfolded position thereof;

FIG. 3 is a back view thereof;

FIG. 4 is a left side view thereof;

FIG. 5 is a right side view thereof;

FIG. 6 is a top side view thereof; and,

FIG. 7 is a bottom side view thereof.

The broken lines, in the figures, represent portions of the towel for workout and beach lounging which form no part of the claimed design.

1 Claim, 4 Drawing Sheets
